UNITED STATES PATENT OFFICE.

IONIA MONFORT SULLIVAN, OF KANSAS CITY, MISSOURI.

DESIGN FOR AN EMBLEMATIC PIN.

Application filed July 13, 1922. Serial No. 3,053. Term of patent 3½ years.

To all whom it may concern:

Be it known that I, IONIA MONFORT SULLIVAN, a resident of the United States, residing at 3108 Brooklyn Ave., in the city of Kansas City, in the county of Jackson, State of Missouri, have invented a new, original, and ornamental Design for Emblematic Pin, of which the following is a specification, reference being had to the accompanying drawing, forming part thereof.

I claim:

The ornamental design for an emblematic pin, as shown.

IONIA MONFORT SULLIVAN.
